UNITED STATES PATENT OFFICE.

HAMILL J. QUEREAU, OF BALDWINSVILLE, NEW YORK.

REINFORCED CONCRETE.

No. 918,366.

Specification of Letters Patent.

Patented April 13, 1909.

Application filed October 8, 1907. Serial No. 396,476.

To all whom it may concern:

Be it known that I, HAMILL J. QUEREAU, of Baldwinsville, in the county of Onondaga, in the State of New York, have invented new and useful Improvements in Reinforced Concrete, of which the following, taken in connection with the accompanying drawings, is a full, clear, and exact description.

This invention relates to certain improvements in reinforced concrete and refers more particularly to concrete arches or arcs of any desired radius such as floor, window and door arches of buildings, viaduct or aqueduct arches and in fact any span which it is desired to bridge with concrete.

In the present method of building concrete arches, it is customary to construct and install a wood form of the required radius which serves as a temporary support upon which the concrete is molded while in a plastic state, the wood form being left in place until the concrete is fully set or seasoned after which the form is removed. This method obviously entails a considerable expense and frequent delay in the prosecution of the work particularly where a large number of arches are to be constructed and in order to save expense of lumber and other material used in the construction of the forms, it not infrequently happens that the contractor or builder will remove such forms before the concrete is sufficiently set to be self-sustaining so that he may reuse the material in the construction of other forms which is more or less liable to cause the concrete structure to warp or become distorted, if not to actually collapse.

The primary object of my invention is to avoid the extra expense of these wood forms and the accompanying liability to accidents by preconstructing and installing a flexible arch of reinforced concrete capable of being deflected or bent to the desired arc and which is self-sustained at its ends upon the piers, I-beams or other end supports and becomes a permanent part of the arch and superstructure of the same or different material.

In other words, I have sought to produce a flexible reinforced concrete form as a new article of manufacture adapted to be made up and carried in stock for different lengths of arc and channeled for different radii so that when bent to the arc, the meeting faces of the segments will abut against each other beneath the bond forming additional chan-

nels above the bond into which the superposed concrete body may be worked or impressed so as to permanently unite the superposed body to the reinforced concrete form and thereby additionally strengthen the form against load strains.

Other objects and uses relating to specific parts of the reinforced concrete will be brought out in the following description.

In the drawings—Figure 1 is a perspective view of a portion of one of my improved reinforced concrete forms or sections for forming an arch. Fig. 2 is a sectional view of a portion of a floor of a building showing my invention as applied to floor arches. Fig. 3 is a sectional view of a further modified manner of supporting the arch, and Fig. 4 is a perspective view of one of the flexible concrete strips and mold in which it is formed, the latter being shown in section.

The reinforced concrete arched sections forming the subject matter of this invention are made in easily portable strips at some locality where the manufacture may be carried on extensively and to which the materials entering into the construction may be economically transported or supplied said concrete strips with their reinforcements embedded therein being preferably made in suitable molds to the desired dimensions for the arches in which they are to be installed, the length of such sections or strips depending upon the span or radius of the arch.

The mold as—1—may be made of wood or any other suitable material and usually consists of a rectangular box open at the top and having its bottom provided with a series of transverse upwardly tapering ribs extending from side to side and of uniform height usually somewhat less than the depth of the box, said ribs being spaced equi-distant apart.

A bed of concrete is placed within the mold upon the bottom in a plastic condition to about the height of the ribs —2— and upon the top face of this concrete is placed a reinforcing bond —3— preferably of woven wire which is flexible and is usually nearly co-extensive with the area of the concrete bed upon which it rests. After the woven wire bond is placed in position in the manner just described and while the underlying bed of concrete is still green or plastic, a superposed bed —5— of the same or similar concrete is placed upon and worked through the meshes of the wire screen bond so as to firmly

knit to and become incorporated with the underlying concrete bed —4—. While this upper bed of concrete is still plastic it is formed by a suitable tool with a series of 5 transverse grooves —6— extending from side to side in vertical alinement with the corresponding ribs —2— but of less depth than the superposed concrete bed —5— so as to leave a solid body of concrete between the 10 grooves and ribs, whereupon the completed concrete strip or section with the bond therein is allowed to set and thoroughly season. After the concrete is thoroughly dry or set it is removed from the mold by simply inverting 15 the latter leaving the concrete section with a series of V-shape grooves —7— formed by the ribs —2— and, therefore, extending from side to side of the concrete strip.

By leaving a solid body of concrete between 20 the bases of the grooves —6— and —7—, the concrete strips are self-sustaining and may be transported from place to place in straight form and when ready to install to form the arch they may be readily flexed at 25 the junction of the grooves —6— and —7— thereby breaking the concrete between the bases of the grooves —6— and screen wire bond —3— which latter ties the segments together in one continuous but flexible strip. 30 The angle of the grooves —7— depends somewhat upon the radius of the arch and is generally made so that when the arch is sprung to the proper arc, the meeting faces of the segments will abut one against the other. The 35 object in forming the additional transverse grooves —6— is to facilitate bending or breaking of the concrete in line with the apexes of the grooves —7— and by breaking the concrete at the bases of the grooves 40 —6— it affords a rough surface to which the superposed concrete structure in the arch will more readily and firmly adhere.

When the strips are flexed or bent in the form of an arc as shown in Fig. —2—, the upper bed will be opened at intervals at the 45 grooves —6— and breaks at the bases of the grooves so that when the superposed plastic

concrete is applied thereto, it will be thoroughly worked into these transverse grooves or openings and against the roughened 50 broken surfaces forming practically a unitary concrete structure, the filling in the groove —6— serving when set to additionally reinforce the arch.

Although I have shown this reinforced concrete strip as formed in a mold having ribs to form the groove —7—, it is obvious that the reinforcing bond —3— may be otherwise embedded in the concrete than in the manner described and that the grooves —7— may be 60 formed by a suitable tool or implement without departing from the spirit of my invention and therefore, I do not limit myself to the precise method of making these reinforced concrete strips hereinbefore described. 65

What I claim is:

1. In combination with the abutments of an arch, a reinforced concrete arch section having its ends resting on said abutments and provided with a reinforcing bond embedded therein between its inner and outer faces, said arch section being composed of longitudinal sections having their adjacent edges beveled inwardly and outwardly from said bond, the adjacent faces abutting 75 against each other below the bond and concrete filling in the spaces between said adjacent faces at the outer side of said bond.

2. A reinforced concrete arch section having a reinforcing bond embedded therein between its inner and outer faces, said arch section being formed with longitudinal V-shaped grooves at opposite sides of the bond and having their apexes located at said bond, the grooves at the outer side being located directly above and parallel with those at the inner side of the bond and extending substantially to said bond. 80 85

In witness whereof I have hereunto set my hand this 28th day of September 1907.

HAMILL J. QUEREAU.
